Attorney

UNITED STATES PATENT OFFICE.

EDWARD MILLER, OF MALTA, MONTANA.

SLAT FOR BINDER APRONS.

1,405,312.

Specification of Letters Patent. Patented Jan. 31, 1922.

Application filed June 5, 1920. Serial No. 386,807.

To all whom it may concern:

Be it known that I, EDWARD MILLER, a citizen of the United States, residing at Malta, in the county of Phillips and State 5 of Montana, have invented certain new and useful Improvements in Slats for Binder Aprons; and I do hereby declare the following to be a full, clear, and exact description of the invention, such as will enable others 10 skilled in the art to which it appertains to make and use the same.

This invention relates to a slat for the apron of a grain binder, and the object is to provide a slat which may be applied in 15 the field, without the use of rivets or other similar securing devices, and one which cannot be loosened from the canvas of the apron, during use.

A further object is to provide a slat which 20 shall be so connected with the canvas strip that straw or weeds will be prevented from passing under the slat, tending to loosen the latter.

A still further object is to provide a device 25 of the type indicated which may be formed of sheet metal, the side walls of the slat being deflected inwardly to form a channel member through which a rod passes, the canvas being looped in the channel element, 30 and retained therein by the rod.

A still further object is to provide a grooved element formed within the body thereof and integrally with the walls of the slat, the groove having communication with 35 a longitudinal slot through which the looped portion of the canvas passes, the looped portion being engaged and retained by a rod received by the grooved portion and retained therein by frictional contact.

40 With the foregoing and other objects in view, the invention consists in the novel construction, combination and arrangement of elements hereinafter described and claimed.

In the accompanying drawing:

45 Figure 1 is a perspective view of the device in operative position and as applied to a section of the apron of a grain binder.

Figure 2 is a view in transverse section, 50 on an enlarged scale, a portion of the belt or apron being shown.

Figure 3 is a perspective view of the slat, partly broken away.

Figure 4 is a view of the key rod, detached.

A section of the apron or belt is shown at

10, the slat as a whole being designated 12, 55 and the key-rod being shown at 14.

The slat is formed of sheet metal and includes a wall 15, oppositely located side walls 16 and 17, and portions 16' and 17' extending at an angle with the elements 16 and 17. 60 A channel member 18 is formed by deflecting inwardly, in the manner shown, the elements 16, 16', 17 and 17', so that an approximately cylindrical tubular element is provided for receiving the looped portion 65 of the apron. A slot 20 communicates with the channel member 18 and the canvas passes through this slot in loop form.

The key rod 14 is received within the loop portion of the apron or belt and within the 70 channel member; and the elements being of the proportions shown, a positive lock is provided.

One end of the rod 14 carries a head 22 which engages the adjacent end of the channel member when the elements are assembled, this head being provided with a rounded surface.

An important feature of the construction is the reinforcement of the channel member 80 by elements 25 in the form of arcuate sleeves or clasp as shown in cross section in Figure 2. The walls of elements 25 and the channel member first referred to are approximately concentric. The slat per se is formed of a 85 continuous sheet of metal, the seam being along the line 26, the elements 25 being separately applied.

Having thus described the invention, what I claim is:—

1. In a device of the class described, a grooved member formed of sheet metal and comprising outer walls and a channel member extending longitudinally between said walls and formed integrally therewith, a reinforcing device for the channel member, and a key rod extending through said channel member for retaining a flexible element therein.

2. A device of the class described comprising a hollow element formed of sheet metal and having outer walls and an inner channel formed continuously with the outer walls, a slot being provided for passing a sheet of flexible material into the inner channel, an arcuate sleeve enclosing said inner channel and extending longitudinally thereof, constituting a reinforcing device, and a

rod for retaining the sheet of flexible material within the channel.

3. A device of the class described comprising an element substantially rectangular in cross section, including outer walls, said walls being deflected inwardly to form a channel member within the body of the rectangular structure, a longitudinally extending reinforcing device for said channel member, a key rod extending through the channel member adapted to retain a looped portion of a flexible element within the channel, and a head on said rod to abut the adjacent end of the channel member.

4. A device of the class described comprising a channel member with an insert opening to receive a flexible loop, a key insertible into said channel member to pass through the loop, and portions extending from opposite edges of the channel member and engaging each other to reinforce the channel member. 15 20

In testimony whereof I affix my signature in presence of two witnesses.

EDWARD MILLER.
